STARTING GEAR FOR INTERNAL COMBUSTION ENGINES

George E. Ramstad, Milwaukee, Wis., assignor to
Nordberg Manufacturing Company, Milwaukee, Wis., a corporation of Wisconsin

Application July 6, 1936, Serial No. 89,173

3 Claims. (Cl. 60—16)

This invention relates to air starting gears for internal combustion engines and particularly reversible four cycle engines. While not limited to utility in connection with Diesel engines the device is intended particularly for that field of use.

For practical reasons, encountered particularly in the marine field, mechanically actuated air starting valves are desired. It is important that the starting gear be set for forward or reverse running by the mere act of setting the reversing valve gear of the engine, and that the air starting gear be rendered wholly inert by the turning off of the starting air and active simply by turning on such air.

The invention meets these requirements and offers a device having other substantial practical advantages which will become apparent as the description proceeds.

In the drawings,—

Fig. 1 is a vertical section through the axis of one cylinder on a plane perpendicular to the crank shaft and showing the starting mechanism for one cylinder.

Fig. 2 is a fragmentary view similar to a portion of Fig. 1 and showing a modification. In this view the parts are shown in the inactive position assumed when the starting air is turned off.

Fig. 3 is a view similar to a portion of Fig. 1, showing a further modification.

A portion of a cylinder is shown at 6 and a portion of the cylinder head at 7. Use of the usual piston connecting rod and crank shaft is contemplated, but these parts are conventional and are not illustrated. The cam shaft is shown at 8 and is driven as usual from the crank shaft at half crank shaft speed.

This shaft ordinarily has cams for actuating the valve gear of the engine, and it will be assumed that this valve gear is of a type which may be set for forward or reverse running by turning the reversing shaft 9 through an angle of 180°. As many valve gears which could be arranged for this purpose are known (including that shown in my Patent No. 2,090,735, granted August 24, 1937), and as the present invention involves the air starting valves and is not affected by the engine valve gear, it is deemed unnecessary to illustrate the reversing valve gear of the engine. The cam 11 on shaft 8 is the air starting cam and is fast on the shaft.

Inserted through head 7 is the housing 12 which seats on shoulder 13 and is held to its seat by yoke 14 drawn down by nuts 15 on studs 16. Only one of the plurality of studs actually used is visible in the drawings. At the lower end of

housing 12 is a seat for the poppet type air inlet valve 17 which has guide wings 18 on its stem to center it in housing 12.

The upper end of the valve stem is shouldered at 19 and is fixed in a sleeve 22 by a nut 21 threaded on its end. Sleeve 22 makes a close sliding fit in the upper end of housing 12 and carries at its upper end a cup-like cylinder 23 in which works a cup-shaped piston 24. A vented cap 25 limits the upward motion of piston 24 and acts as a seat for spring 26 which urges the piston downward. A link 27, acts in thrust with piston 24 and its lower headed end is retained by clip 28. Spring 20 urges valve 17 closed.

The upper end of link 27 is pinned at 29 to rock lever 31 pivoted at 32. The other end of lever 31 is pinned at 33 to push rod 34, whose lower end is guided by a swinging link 35 pinned thereto at 36 and fulcrumed at 37 to a crank arm on reversing shaft 9.

At its lower end push rod 34 carries a roller 38 which is confined in the angular slot 39 on rocker 41. Rocker 41 is fulcrumed at 42 and has two cam followers to coact with cam 11, one for forward and the other for reverse running.

These followers take the form of rollers 43 and 44. Roller 43 is conditioned to become effective when roller 38 is in the inner end of slot 39 (i. e., the end toward cylinder 6, as shown in Fig. 1) and roller 44 is conditioned to become effective when shaft 9 is turned 180° from the position shown in which case roller 38 is in the outer end of slot 39. Neither roller is, however, actually effective to coact with cam 11 unless the starting air is turned on.

The starting air bottle or other source of starting air under pressure is indicated at 45 and supplies air to a three-way valve 46, which in the starting position shown in Fig. 1 connects source 45 with passage 47. In running position valve 46 interrupts this connection and vents passage 47 to atmosphere. Passage 47 leads through port 48 to valve 17 and by passage 49 in the stem of valve 17 communicates with cylinder 23 beneath piston 24.

Consequently, when starting air is turned on, piston 24 is forced up overpowering spring 26, and increasing the distance between valve 17 and pivot 29. With shaft 9 in the position shown this tilts rocker 41 so that roller 43 coacts with cam 11. With shaft 9 turned 180° from the position shown roller 44 would coact with cam 11 upon the admission of starting air. When cylinder 23 is vented, as it is in running position of valve 46, the rocker 41 is held in an intermediate

position in which both rollers 43 and 44 clear cam 11.

The parts are so dimensioned and arranged that one of the rollers 43, 44 operates the valve in proper time for forward running and the other in proper time for reverse running. The air starting valve mechanism times the admission of starting air to the cylinder. As is usual in such mechanisms, the regular exhaust valve for the cylinder controls the exhaust of starting air from the cylinder.

By confining the roller 38 in slot 39 piston 24 controls rocker 41. As shown in Fig. 2 a spring 51 can be used to bias the rocker to its inert position in which both rollers clear the cam. In this figure parts similar to those in Fig. 1 are similarly numbered with the letter *a*. The slot 39 becomes an angular thrust surface 39a with which roller 38a acts in unidirectional thrust.

20 The operation is essentially similar to that already described.

In Fig. 3 a further modification is shown. Instead of changing the effective length of the link 27 which connects valve 17 with rocker 31, as in Fig. 1, the axis of the fulcrum for rocker 31 is shifted with similar effect. This arrangement, unlike that shown in Fig. 1, requires only one air motor to shift the rockers for a plurality of cylinders because with aligned cylinders all the 30 fulcra can be shifted as a unit.

In Fig. 3 the parts corresponding to those numbered 6 to 21 and 34 to 48 of Fig. 1, are unchanged. Such of these parts as are visible in Fig. 3 are numbered as in Fig. 1 but with the letter *b*. The parts 34a to 44a of Fig. 2 can be substituted as before.

Nut 21b and shoulder 19b afford a rigid connection between valve 17b and sleeve 22b, the sleeve being guided in housing 12b. A spring 20b urges valve 17b closed.

40 A link 27b pinned to sleeve 22b is pinned at 29b to rock lever 31b whose other end is pinned at 33b to push rod 34b. Rod 34b is functionally identical with rod 34 of Fig. 1 and rod 34a of Fig. 2.

45 Rocker 31b is mounted on the journal 32b, which is eccentrically mounted on shaft 50 carried in the bearing pedestals 59. An arm 52 fast on shaft 50 is connected by link 53 with piston 54, the piston working in cylinder 55. A spring 56 urges piston 54 downward. A vented cap 57 limits upward movement of the piston and the lower end of the cylinder limits its downward movement.

55 Cylinder 55 is mounted on head 1b and a branch 58 of port 47b communicates with its lower end.

The normal position of piston 54 is at the lower end of cylinder 55. Journal 32b is then in its 60 raised position and the cam follower shifts to inactive position. When starting air is turned on the piston 54 moves up to the position of Fig. 3, lowering journal 32b and rendering the cam follower active (see position indicated in Fig. 1).

65 In a multi-cylinder engine only one piston 54 and cylinder 55 need be used, since a single shaft 50 can carry journals 32b, one for each cylinder.

Other modifications within the scope of the invention are possible and are contemplated.

What is claimed is,—

1. The combination of an internal combustion engine, including a working space, a cam shaft, 5 and a reversing member shiftable between forward and reverse settings; a starting cam on said shaft; a rocker having two cam followers, one for each direction of starting, said followers being brought selectively into coactive relation 10 with said cam by reverse tilting of said rocker; a normally closed valve for admitting starting air to said working space; driving connections between said rocker and said valve, said connections being displaceable between two positions, 15 in which respectively they are conditioned to tilt the rocker reversely; connections through which the reversing member according to its setting, sets said driving connections selectively in said two positions; a shiftable element associated 20 with said driving connections and having a normal position in which said connections irrespective of their position, set said rocker in an intermediate inactive position, and a starting position in which said connections tilt said rocker 25 in one or the other direction as determined by the position of the reversing member; means biasing said element to said normal position; a motor for shifting said element to the second position; and means arranged to supply air to 30 said starting valve and energize said motor, and alternatively to cut off said supply and de-energize said motor.

2. The combination of an internal combustion engine, including a working space, a cam shaft, 35 and a reversing member shiftable between forward and reverse settings, a starting cam on said shaft; a rocker having two cam followers, one for each direction of starting, said followers being brought selectively into coactive relation 40 with said cam by reverse tilting of said rocker; a normally closed valve for admitting starting air to said working space; driving connections between said rocker and said valve, said connections being displaceable between two positions, in which respectively they are conditioned to tilt the rocker reversely; connections through which the reversing member according to its setting, sets said driving connections selectively in said two positions; a shiftable element associated 45 with said driving connections and having a normal position in which said connections irrespective of their position, set said rocker in an intermediate inactive position, and a starting position in which said connections tilt said rocker in one or the other direction as determined by the position of the reversing member; means biasing said element to said normal position; an air motor for shifting said element to the second position; and means operable to supply air under 50 pressure to said valve and to said motor, and alternatively to cut off said air and vent said motor.

3. The combination defined in claim 2, in which the driving connections have a two way driving relation with said rocker, whereby the driving connections serve to hold the rocker in said intermediate inactive position.

GEORGE E. RAMSTAD.
